JACK W. EKRE AND SAMUEL E. DIME, OF MINNEAPOLIS, MINNESOTA

REVOLVING DOOR

Application filed August 29, 1928. Serial No. 302,804.

This invention relates to certain improvements in revolving doors; and the nature and objects of the invention will be readily recognized and understood by those skilled in the art in the light of the following explanation and detailed description of the accompanying drawings illustrating what I now believe to be the preferred embodiments or mechanical expressions of the invention from among various other forms, arrangements, combinations and constructions of which the invention is capable within the spirit and scope thereof.

With doors of the revolving types considerable difficulties are encountered in use through injuries to persons entering or leaving the same, caused by the continued rotation or revolution of the doors after passage of a person therethrough, and a general object of this invention is to eliminate the foregoing difficulties by the provision of a revolving door with which the speed of rotation is entirely under the control of the operator or person passing therethrough, and which is so constructed and arranged that it will quickly cease to rotate or revolve and come to rest after a person has passed therethrough and left the door, thus permitting the next person to enter with the door at rest.

A further object of the invention is to provide an arrangement and construction of revolving door which normally is held against rotation by suitable braking mechanism, but which is provided with release mechanism operable by a person passing through the door for releasing the braking mechanism to permit the door being rotated at a rate or speed controlled and as may be desired by the person revolving the same and passing therethrough.

A further object of the invention is to provide an efficient braking and speed controlling mechanism for doors of the revolving type, together with mechanism for applying and releasing such mechanism which is under the control of a person revolving and passing through the door.

Another object of the invention is to provide mounting and supporting bearing ar-

rangement for the lower end of a revolving door structure, which arrangement supports the door and presents bearings for taking both thrust and radial forces, so that the door is rigidly but freely rotatably mounted and capable of being easily revolved with a minimum of force or pressure applied thereto.

A further object of the invention is to provide mechanically simple and efficiently operating mechanism for a revolving door in order to carry out the foregoing general objects.

With the foregoing objects, and certain other objects and results in view which will be readily recognized from the following explanation, the invention consists in certain novel features in construction and in combination and arrangement of parts, as will be more fully and particularly referred to and specified hereinafter.

Referring to the accompanying drawings in which similar reference characters refer to corresponding parts throughout the several figures.

Fig. 1 is a view in elevation of a door embodying the invention in mounted operative position, with a portion thereof removed to disclose a vertical section therethrough taken on the lines 1-1 of Fig. 3.

Fig. 2 is an enlarged vertical section through the mounting of the lower end of the door upon which the same revolves, and showing the arrangement and construction of bearings therefor.

Fig. 3 is an enlarged horizontal section taken through the door brake operating mechanism at the intermediate portion of the rotating column.

Fig. 4 is a view in elevation showing the operating mechanism, with a portion thereof in vertical section taken on the line 4-4 of Fig. 3.

Fig. 5 is a vertical longitudinal section through the upper end mounting of the door of the invention, and showing the brake and controlling mechanism therefor.

Fig. 6 is an enlarged view in top plan of Fig. 5, showing particularly the manner of mounting the brake disks or rings.

Fig. 7 is a detail view in end elevation of

the operating bar and lever shown in Fig. 4.

Fig. 8 is a horizontal section through the central column, showing the doors mounted thereon, taken on the line 8—8 of Fig. 5.

- 5   A possible form and construction of revolving door embodying the several features of the invention is disclosed in Fig. 1 of the drawings as installed and mounted in operative position within the usual or any desired 10   revolving door casing, which in the present example embodies the opposite side curved or arcuate casing walls C, the casing top wall or ceiling T and the floor or other supporting surface F. The revolving door is mounted 15   disposed in the usual manner between side walls C for rotation around and on a vertical axis centrally of said walls and extending between the floor F and the ceiling T, as will be readily understood by those familiar with 20   these general types of doors.

According to the invention a central rotating shaft or column 3 is provided mounted and supported at its lower end on and from floor F and extending upwardly to and 25   mounted at its upper end on or in the ceiling T. This rotating central column comprises two tubes or sections 3a and 3b secured together at their adjacent ends in longitudinal alinement by means of the housing or casing 3c forming a coupling and connection between these tubes or sections of column 3, as will be clear by reference to Figs. 1 and 4 of the drawings in particular. Flanged collars 3c and 3d are rigidly fixed over and secured 30   to the upper and lower ends of column 3, respectively, and each of these collars is provided with the vertical bores 3f and 3g through the flange thereof at opposite sides of the column 3 to receive and form alined 35   upper and lower bearings at opposite sides of the column. These upper and lower collars 3c and 3d are also provided at opposite sides from that of the bearings 3f and 3g with pairs of spaced laterally projecting plates 40   45   or fins 3h and 3i. Opposite doors 1 and 2 are provided with the upper and lower vertically disposed alined pivots 1a and 2a, respectively, adjacent their inner edges, which fit into and are pivotally received by the 50   55   spaced vertically alined bearings 3f and 3g, so that the doors 1 and 2 are pivotally mounted for horizontal swinging on column 3. Opposite doors 4 and 5 are received in the spaced upper and lower plates 3h and 3i and 60   65   are thereby secured and fixed in rigid position extending from the column 3 at substantially right angles to the doors 1 and 2. The doors 1 and 2 are pivotally mounted to permit of their being folded or swung into positions against and substantially parallel with the doors 4 and 5 so that the passage closed by the doors in normally extended operative position, is open for uninterrupted passage therethrough, with the doors 1 and 2 swung 65   to folded positions.

The rotatable mounting of the lower end of column 3 on floor F is carried out in the present instance by providing a plug or block 9 accurately and rigidly fitted within the lower end of tube 3b of column 3, which plug 9 has an enlarged radial flange 9a fitted against the lower end edge of tube 3b, and which plug is also formed with the reduced diameter axially alined portions 9b and 9c extending and depending downwardly therefrom. A 75   thrust bearing 10 of the ball type in the present instance, is mounted on and around the reduced portion 9b of plug 9, and a radial bearing 11 also of the ball type is mounted on and around the reduced portion 9c and is 80   confined thereon against the shoulder 9d by means of the nut 12 secured and locked on the lower end of plug 9. A thimble or cup like member 13 is secured and mounted on the floor F and receives the radial bearing 11 of 85   column 3 within the cylindrical bore 13b thereof, into which bore the bearing 11 accurately fits and bears against to carry radial forces and prevent lateral or radial movements of column 3. The thrust bearing 10 is received 90   and fits into the upper end of cup 13 and fits and is supported on a shoulder 13a formed around the upper end of bore 13b. The bearings 10 and 11 thus carry and support the column 3 and the doors 1, 2, 4 and 5 thereon, 95   for rotation on and around cup member 13, with the lower collar 3d of column 3 fitting over and around, and spaced a slight distance from the exterior wall of cup member 13. The thrust bearing 10 supports the column 100   and doors, and the radial bearing 11 cares for radial forces and maintains the column in the desired vertical and rigid position.

The upper end of the column 3 is provided with a bushing 6 accurately and rigidly fitted 105   and secured within the upper end of the tube 3a of column 3 and this bushing is provided with an upwardly extending annular projection 6b, and further provided with an axial bore 6a extending through the bushing and the annular projection 6b. An actuating shaft 7 extends downwardly through the bore 6a in bushing 6 and bushing projection 6b for sliding movement or reciprocation therethrough, but keyed or otherwise mounted to 110   bushing 6 and projection 6b for rotation therewith, and this shaft 7 extends downwardly through the column into and is slidably received in a bearing 3j formed at the lower end of housing 3e.

A brake case 8 is secured to the ceiling or upper wall T of the door casing above surrounding and axially alined with actuating shaft 7 and the column 3. This brake case 8 is formed with a depending sleeve forming an axial bore 8a therethrough into which the projection 6b of column bushing 6 extends and fits, with the shaft 7 extending upwardly therethrough and thereabove. A drum 15 is mounted slidably on the upper 115   120   125   130   135

end of shaft 7 for rotation therewith, as by keying the same to the shaft, and is disposed within the brake case 8. A compression disk 16 is secured or keyed onto the shaft 7 above drum 15 and is longitudinally adjustably fixed onto the upper end of this shaft by means of nut 17 and the lock nut 18 on the outer end of the shaft.

The braking mechanism includes a multiplicity of thin metal rings or disks 14 arranged in a horizontal plane one above the other within the brake case 8 and alternate rings or disks are secured to the brake case 8 against rotation by means of the projections 14a on the disks and the recesses 8b in the case 8. The remaining or alternate disks are secured for rotation with the drum 15 by means of the projections 15a on such disks projecting into recesses 15b in the drum 15, as clearly shown by Fig. 6 of the drawings, when taken in connection with Fig. 5. The arrangement is such that when the shaft 7 is drawn or moved downwardly it carries compression disk 16 downwardly into the brake case 8 between the outer wall of case 8 and the drum 15, onto and forcing the brake rings or disks 14 together binding or locking the shaft against rotation, and when shaft 7 is raised or moved upwardly the disks 14 expand or separate to release shaft 7 for rotation.

A spring compressing collar 19 is fixed to the shaft 7 within column 3 spaced inwardly a distance from the bushing 6 and a compression spring 20 is mounted around shaft 7 between collar 19 and the inner end of bushing 6. This mounting and arrangement of spring 20 is shown particularly by Fig. 5 with the spring in its compressed position, that is with the shaft raised and the brake rings or disks 14 in their expanded, separated or non-braking and non-locking position.

The shaft 7 at that portion within casing 3e between the column sections 3a and 3b is formed with rack teeth 7a therearound. This casing is also provided with the spaced bearings 3k extending laterally therefrom tangentially with respect to shaft 7 and each having rotatably mounted therein and extending therethrough the horizontally disposed shafts 21 which at their inner ends are provided with the pinions 22 fixed thereon in mesh with the rack teeth 7a of shaft 7 at diametrically opposite sides of this shaft, as clearly shown by Figs. 3 and 4 of the drawings. The bearings 3k and the shafts 21 mounted therein extend outwardly along the sides of the doors, respectively, mounted on the column 3, and each shaft 21 is secured at its outer end to a lever 23 which depends therefrom. Each lever 23 is formed at its outer lower end with a bifurcated or forked portion 23a.

Each of the doors 1, 2, 4 and 5 is provided with the horizontally spaced brackets 26 secured on a side thereof and having the alined

bearings 26a at their upper ends which are alined with the bearings 3k and shafts 21 respectively, carried by the column 3. A shaft 25 is mounted extending between each pair of door brackets 26 and is rotatably mounted in the bearings 26a, with the inner end of shaft 25 extended a distance beyond the inner bracket bearing toward and adjacent shaft 21 with the lever 23 thereon. A lever 24 is mounted on the inner end of each shaft 25 adjacent lever 23 and terminates at its lower end in a lateral crank arm 24a which extends and slidably fits into and is received by the lower forked end of lever 23. By this arrangement therefore oscillation of a shaft 25 will swing its lever 24, which in turn swings lever 23 and rotates a shaft 21 to cause raising or lowering of the brake mechanism operating shaft 7 in column 3, through a pinion 22 in mesh with shaft 7 rack teeth 7a. Manual operating handles or bars 27 are secured at their opposite ends between a bar of levers 28 which are fixed to shaft 25 between brackets 26. The compression spring 20 normally forces shaft 7 downwardly to maintain compression disks 16 in position rendering the brake mechanism operative to hold column 3 against rotation. This normal downward retention of shaft 7 causes a rotation and resulting position of shaft 21,

levers 23 and 24 with shaft 25 to swing outwardly from each door. Hence, it follows that by forcing or pressing a bar 27 inwardly toward its door, the shaft 21 will be rotated and through pinion 22 in mesh with the rack teeth 7a on shaft 7, this shaft will be raised against the tension of spring 20 to elevate or raise the brake mechanism compression disk 16 and expand the brake disks or rings 14 into position disengaged and permitting free rotation of column 3 with the doors thereon, by pressure exerted on the doors through a bar 27 by a person wishing to revolve the doors to pass therethrough. By controlling the extent of pressure on a bar 27, the degree or extent of braking action on shaft 7 can be determined and the rate of rotation of shaft 7 with doors 1, 2, 4 and 5 controlled.

The invention provides a further feature in that the swinging doors 1 and 2, can be swung or opened to their operative and inoperative positions, and the actuating handle bars with their shafts 25 and crank levers 24 disconnected and connected with the levers 23 and shafts 21, by the act of swinging these doors, through the provision of the slotted end levers 23 which permit the crank arms 24a to swing outwardly and downwardly therefrom when the doors are folded or swung to inoperative positions and to swing freely back there into and coupled therewith when the doors are swung outwardly or unfolded into operative position.

In order to lock and secure the folding doors 1 and 2 into extended operative posi-

tion on column 3 with respect to the fixed doors 4 and 5, the invention provides a series of link members 30 detachably coupled between the doors adjacent their inner edges, as clearly shown by Figs. 1 and 8 of the drawings.

The revolving door above described and embodying the features of the invention, is thus normally maintained and held against 10 rotation by the brake mechanism at the upper end thereof, which is maintained in operative braking position by the compression spring 20 drawing and forcing shaft 7 downwardly to cause operation of the brake mechanism 15 by the pressure of the brake compression disk 16. Now when a person desires to revolve the doors and pass through the opening closed thereby he presses upon and against one of the levers or bars 27 to rotate shaft 21 20 which is coupled therewith and through pinion 22 and rack teeth 7a, raises shaft 7 against spring 20 to release the brake mechanism and permit free or controlled rotation or revolution of the doors with column 3. 25 The speed of rotation or revolution of the doors and their carrying column 3 can be controlled and determined by the person operating the same through the degree or extent of pressure and resulting elevation of shaft 7, 30 which he places on the handle bar 27, as will be readily apparent from the drawings in connection with the foregoing description. The lower bearing mounting and arrangement for column 3 insures a rigid but readily 35 rotatable column for carrying the doors, yet which is mechanically simple and efficient in operation under the varying conditions of use.

It is evident that various changes, modifications, variations, and substitutions might be resorted to without departing from the spirit and scope of my invention, and hence we do not desire to limit ourselves in all particulars to the exact and specific dis- 45 closures hereof.

What we claim, is:—

1. In a door of the revolving type, a rotatably mounted vertical column, doors mounted thereon for rotation therewith, friction 50 brake mechanism operatively engaged with and for arresting rotation of said column, spring means normally rendering said brake mechanism operative to engage and hold the column against rotation, and means for releasing said brake mechanism against said spring means to permit free rotation of the column and doors.

2. In a door of the revolving type, a rotatably mounted vertical column, doors mounted 60 thereon for rotation therewith, brake mechanism operatively engaged with and for arresting rotation of said column, spring means normally rendering said brake mechanism operative to engage and maintain the column against rotation, and means operable

from said doors by pressure for releasing said brake mechanism against said spring means to permit rotation of the column, said spring means rendering the brake mechanism operative to stop rotation of the column upon removal of pressure from said pressure operated means. 70

3. In a door of the revolving type, a rotatably mounted vertical column, doors mounted thereon for rotation therewith, brake mechanism mounted at the upper end of said column for arresting and controlling rotation thereof, an actuating shaft on the column for said brake mechanism, a spring normally operating said shaft to apply said brake mechanism to the column, and manually operated mechanism carried by said doors for operating said brake actuating shaft against the action of said spring to release the brake mechanism and permit rotation of the column and doors. 75 80 85

4. In a door of the revolving type, a rotatably mounted vertical column, doors mounted thereon extending radially therefrom for rotation therewith, an actuating shaft mounted extending upwardly through and above the upper end of said column for reciprocation therein, brake mechanism at the upper end of said column for application thereto to arrest and control rotation of the column, said actuating shaft operatively coupled to said brake mechanism for applying and releasing the same, a spring normally maintaining said shaft in position applying the brake mechanism, and door carried manually operable means for moving said shaft against said spring to release the brake mechanism and permit rotation of the column and doors. 90 95 100

5. In a door of the revolving type, a rotatably mounted vertical column, doors mounted on said column extending radially therefrom for rotation therewith, a shaft axially mounted in said column extending outwardly through the upper end thereof for reciprocation in and rotation with the column, brake mechanism at the upper end of the column for application thereto to arrest rotation of the column, said shaft operatively coupled with said brake mechanism for applying and releasing the same by reciprocating the shaft, a spring acting on said shaft to normally force the same to position applying said brake mechanism, said shaft formed with 110 115 120 rack teeth thereon within the column below the upper end thereof, shafts disposed transversely of the column at opposite sides of said shaft, a pinion on each transverse shaft in mesh with the rack teeth on said brake operating shaft, and manually controlled mechanism carried by each door and operatively connected with said transverse shafts, respectively, for selective operation to move said axial shaft against said spring to release 125 130

said brake mechanism and permit rotation of said column and doors.

6. In a door of the revolving type, a rotatably mounted vertical column, diametrically opposite pairs of doors carried by and extending radially from said column, one pair of said doors fixed and the other pair pivotally mounted for folding to position along and substantially parallel with the other doors, respectively, brake mechanism for arresting rotation of said column and doors, brake actuating mechanism for applying and releasing said brake mechanism, and manually operated mechanism carried by each door and connected with said brake actuating mechanism for operating the same to apply and release the brake mechanism, the manually operable mechanism carried by the pivoted doors separably connected with said brake actuating mechanism to permit swinging of said doors to and from folded positions.

7. In a door of the revolving type, a rotatably mounted vertical column, doors carried by said column for rotation therewith, brake mechanism at the upper end of said column for arresting rotation thereof, a brake actuating shaft extending upwardly through the column and connected with said brake mechanism for applying and releasing the same, shafts extending transversely through said column disposed tangentially of said actuating shaft at diametrically opposite sides thereof, a pinion on each of said tangential shafts, the actuating shaft formed with rack teeth in mesh with said pinions, and manually operated mechanism carried by each door operatively connected with said tangential shafts, respectively, for manual operation to rotate said tangential shafts and cause operation of said actuating shaft to apply and release said brake mechanism.

8. In a door of the revolving type, a rotatably mounted vertical column, diametrically opposite pairs of doors carried by and extending radially from said column, brake mechanism for arresting and controlling the speed of rotation of said column, an actuating shaft reciprocally mounted in said column for rotation therewith, said shaft coupled with said brake mechanism for applying and releasing the same, rotary shafts extending through said column disposed tangentially of said actuating shaft, pinions on the inner ends of said tangential shaft disposed at opposite side of the actuating shaft, respectively, rack teeth on the actuating shaft in mesh with said pinions, a lever on the outer end of each tangential shaft and having a forked outer end, a horizontally disposed shaft on the side of each door substantially in line with the adjacent tangential column shaft, respectively, a crank lever on each door shaft slidably engaging in the forked end of the adjacent tangential shaft

lever, and an operating member on each door shaft for oscillating the same.

9. In a door of the revolving type, a rotatably mounted vertical column, doors mounted on said column for rotation therewith, a bushing having an axial bore fixed in the upper end of said column, a shaft reciprocally mounted extending through the bore of said bushing into the column, said shaft rotatable with the bushing and column, a brake drum slidably mounted on the outer end of said shaft, a fixed brake case supported independently of the column, brake discs carried by the drum, brake discs carried by the brake case, a compression disc fixed on the outer end of the shaft for movement therewith to and from position forcing said brake case and brake drum discs into braking relation, arresting rotation of the column, a spring normally forcing the shaft downwardly to bring said discs in braking relation, and means operable from each door for forcing the shaft outwardly against said spring to release the brake discs and permit rotation of the column and doors.

10. In a door of the revolving type, a rotatably mounted vertical column, doors mounted thereon for rotation therewith, friction brake mechanism operatively associated with said column for arresting rotation thereof, said brake mechanism normally operative to engage and maintain the column against rotation, and means operable from said doors to release said brake mechanism from braking engagement with said column and permit rotation of said column and doors.

11. In a door of the revolving type, a rotatably mounted vertical column, doors mounted thereon for rotation therewith, brake mechanism operatively associated with said column for arresting rotation thereof, means normally rendering said brake mechanism in operative braking engagement with and maintaining said column against rotation, and mechanism operable from said doors for releasing said brake mechanism for braking engagement with the column to permit rotation of said column and doors.

12. In a door of the revolving type, a rotatably mounted vertical column, doors mounted thereon for rotation therewith, brake mechanism operatively associated with said column for braking engagement therewith to arresting rotation thereof, a shaft on said column for operating said brake mechanism to apply and release the same to and from braking engagement with the column, and manually controlled mechanism carried by said doors for actuating said brake operating shaft.

13. In a door of the revolving type, a rotatably mounted vertical column, doors mounted thereon for rotation therewith, brake mechanism operatively associated with said column for breaking engagement

with the column to arrest rotation thereof, and manually controlled means carried by said doors and operatively coupled with said brake mechanism for operating said mechanism, to release or apply the same.

14. The combination with a revolving door, of brake mechanism operatively associated therewith for braking engagement with the door to arrest rotation thereof,

10 means normally rendering said brake mechanism operative to arrest rotation of the door, and manually controlled mechanism carried by the door and operatively coupled with the brake mechanism for releasing the

15 latter to permit rotation of the door, the said means applying the brake mechanism to arrest rotation of the door upon release of the said manually controlled mechanism.

16. In a door of the revolving type, a ro-

20 tatably mounted vertical column, doors mounted thereon extending radially therefrom for rotation therewith, a brake mechanism operatively associated with the column and including a brake member carried by

25 the column for rotation therewith, said brake mechanism normally operative with said brake member in braking engagement to maintain the column against rotation, and release means for said brake mechanism in-

30 cluding means carried by said doors and actuated by pressure applied thereto to rotate the doors.

17. In a door of the revolving type, a ro-

35 tatably mounted vertical column, doors mounted thereon extending radially therefrom for rotation therewith, a brake mechanism operatively associated with the column adjacent one end thereof and normally in operative brake applying relation there-

40 with to maintain the column against rotation, and release means for said brake mechanism including means carried by said doors and actuated by pressure applied thereto to rotate the doors.

45 18. In a door of the revolving type, a ro-

50 tatably mounted vertical column, doors mounted on said column for rotation therewith, a brake mechanism operatively associated with the column and including a brak-

55 ing member mounted on and carried by the column for rotation therewith, means normally holding said brake mechanism operative with the column carried braking mem-

ber in braking engagement to maintain the column against rotation, and release means for said brake mechanism carried by said doors and actuated by pressure applied thereto to rotate the doors.

60 19. In a door of the revolving type, a ro-

65 tatably mounted vertical column, doors mounted on said column for rotation therewith, a friction brake mechanism operatively associated with said column adjacent one end thereof for arresting rotation of the column,

braking member carried by and rotatable with the column and a fixed braking member adjacent said column carried member for friction braking engagement therewith, means normally rendering said braking mechanism operative with said braking members in braking engagement to stop rotation of the column, and means for releasing said first mentioned means to render the

70 brake mechanism inoperative with the braking members disengaged to permit rotation of the column and doors, said releasing means including operating mechanism therefor carried by said doors and actuated by pressure applied thereto to rotate the doors.

75 Signed at Minneapolis, county of Hennepin, State of Minnesota, this 9th day of Au-

80 gust, 1928.
